AUTOMATIC CLOTHESLINE FASTENER

Filed Nov. 8, 1929

George H. Miller
INVENTOR
BY Victor J. Evans

WITNESS *J. T. L. Wright*

UNITED STATES PATENT OFFICE

GEORGE H. MILLER, OF DECATUR, ILLINOIS

AUTOMATIC CLOTHESLINE FASTENER

Application filed November 8, 1929. Serial No. 405,773.

This invention relates to a clothes line gripping device and more particularly to a device for gripping one end of a tautened clothes line so as to hold the line taut without the necessity of tying knots therein or providing any cumbersome means for accomplishing this result, the invention contemplating a clamping device of such a character that there will be no likelihood of the line becoming loosened or disengaged from the device in the event of a high wind.

Another object of the invention is to provide a clamping device for a clothes line which will operate automatically to clamp the line when the end of the line which is to be clamped is pulled to an extent to render the remainder of the line taut, and then released, so that it is unnecessary to employ any means requiring adjustment in order to secure this end of the line.

Another object of the invention is to provide a device for the purpose stated which may be employed to render taut a clothes line stretched in either one of two directions, so that when it is desired to use the device, the line may be lead to the device from any fixed point of connection for the other end of the line, when found convenient.

This invention also consists in certain other features of construction and in the combination and arrangement of the several parts, to be hereinafter fully described, illustrated in the accompanying drawing and specifically pointed out in the appended claim.

In describing my invention in detail, reference will be had to the accompanying drawing wherein like characters denote like or corresponding parts throughout the several views, and in which:

Figure 1 is a view in side elevation of the clamping device embodying the invention, the view illustrating a portion of the clothes line clamped in the device.

Figure 2 is an end elevation of the device.

Figure 3 is a vertical sectional view taken substantially on the line 3-3 of Figure 1 looking in the direction indicated by the arrows.

Figure 4 is a similar view on the line 4-4

of Figure 1 looking in the direction indicated by the arrows.

Figure 5 is a view similar to Figure 1 and illustrating the manner in which the device may be arranged for tautening a line extending in a direction opposite to the direction of extent of the line shown in Figure 1.

The device embodying the invention comprises an attaching plate 1 which is preferably provided with substantially circular extensions 2 at its lower corners, and an upward extension 3 at its upper side. There is formed or provided, upon the outer face of the plate 1, which plate is to be disposed at its other face against any suitable fixed support and secured thereto in any suitable manner, an outwardly projecting gripping head indicated by the numeral 4 and this head is provided at its upper face with a plurality of transversely extending corrugations, indicated by the numeral 5. Each of the members 2 is provided with an outstanding cylindrical boss 6 having an opening 7 formed therein, the opening extending also through the portion 2, and a pulley 8 may be rotatably mounted upon the boss 6 of either of the portions 2, and is provided at its outer side with a peripheral flange 9 so that the clothes line passed over the pulley will be prevented from leaving the same. A washer 10 of greater diameter than the boss 6 is disposed against the outer end of the boss and an ordinary wood screw 11 may be fitted through the washer and into the bore 7 and threaded at its entering end into the said fixed support, as best shown in Figure 4 of the drawing.

By reference to Figure 1 of the drawing it will be observed that the upper side of the pulley 8 is located in substantially a horizontal line with the upper corrugated surface 5 of the head 4 and it will also be observed by reference to this figure that the clothes line, indicated by the reference letter L is to be lead longitudinally over the corrugated face 5 of the head 4 and thence over the pulley 8.

In order that the clothes line may be automatically gripped as above stated, a gripping member, indicated in general by the numeral 12 is provided and this member com-

prises a flat sided segmental body 13 having transverse corrugations 14 on its arcuate edge. This member is provided at its upper end with an approximately circular head 15 and this head is formed with an opening 16 adapting the member 12 to be pivotally suspended upon a stub shaft 17 formed or provided upon the outer face of the portion 3 of the member 1, a washer 18 being disposed against the outer end of the stub shaft 17 and a wood screw 19 being fitted through this washer and through an opening in the said stub shaft 17 and in the member 3 and threaded into the fixed support.

15 From the foregoing description of the invention it will be understood that by pulling upon the portion of the line L which is shown depending in Figures 1 and 2 of the drawing, the line at the other side of the pulley 20 will be caused to run between the corrugated face 5 of the head 4 and the corrugated edge 14 of the member 12, and it will be also evident that as soon as the first mentioned portion of the line is released, the weight of the line or that together with the clothes hung thereon, will result in a slight backward movement of the line, whereupon the contact of the corrugated edge 14 of the member 12 with the line will result in a gripping of the portion of the line which is between the edge 14 and the corrugated face 5, whereupon the line will be held taut.

In Figure 1 the line is shown as being lead from the left side of the pulley 8 but the line 35 may be lead in the opposite direction by removing the screw 11 and pulley 8 and fitting the pulley onto the other boss 6, and then fitting the screw 11 through the said other boss, the member 12 being swung about this 40 pivot so as to then occupy the position shown in Figure 5 of the drawing.

What I claim is:—

A clothes line clamping device comprising an attaching plate, a fixed gripping member 45 upon said plate having a gripping face member, over which the line is to be drawn in tautening the same, bosses upon the said face of the attaching member at opposite ends of the gripping member, a pulley interchangeably mounted upon the said bosses and over which and the face of the fixed gripping member the clothes line is to be drawn, and a gripping member pivotally mounted for swinging movement, and having a gripping 50 edge for coaction with either end portion of the gripping face of the gripping member, in the swinging adjustment of the said pivoted gripping member to grip the clothes line between the gripping face of the fixed gripping member and the gripping edge of the pivoted gripping member when the gripping member is in either position of its pivotal adjustment.

GEORGE H. MILLER.
